UNITED STATES PATENT OFFICE.

ARTHUR B. CLUNIES, OF ROCHESTER, NEW YORK, ASSIGNOR TO SILL STOVE WORKS, OF ROCHESTER, NEW YORK, A CORPORATION OF NEW YORK.

DESIGN FOR A CENTERPIECE FOR STOVE-TOPS.

SPECIFICATION forming part of Design No. 35,302, dated November 19, 1901.

Application filed August 23, 1901. Serial No. 73,101. Term of patent 14 years.

To all whom it may concern:

Be it known that I, ARTHUR B. CLUNIES, a citizen of the United States, and a resident of Rochester, in the county of Monroe and State 5 of New York, have invented and produced a new and original Design for a Centerpiece for Stove-Tops; and I do hereby declare the following to be a full, clear, and exact description of the same, in connection with the accompanying drawings, forming a part thereof.

My design consists in the general shape and configuration of a stove-top center illustrated in the drawings, of which—

Figure 1 is a perspective view of a center-casting constructed in accordance with my design, and Fig. 2 is a top plan view thereof.

Similar reference-letters in the two figures indicate similar parts.

A stove-top centerpiece constructed in accordance with my design consists of a body portion having a substantially flat top A. The one end a is broader than the other b and has the end face extending downwardly and

provided with cut-out portions c. At the rear sides of the centerpiece are the faces D, 25 sloping outwardly to a shelf or flange d, which also extends around the end b. Arranged upon the shelf d are the projections E, having the curved or rounded upper surfaces, as shown. The sides of the body curve 30 outwardly at the forward end, forming the curved parallel faces F f, between which is a narrow face G, the latter lying between the face f and the top A. Located between the outwardly-curving portions at the forward 35 end of the top is a recess H.

Having described my invention, what I claim as new, and desire to secure by Letters Patent, is—

The design for a centerpiece for stove-tops, 40 substantially as herein shown and described.

ARTHUR B. CLUNIES.
